UNITED STATES PATENT OFFICE.

WILMER A. REIN, OF PLEASANT SPRINGS, WISCONSIN.

LICENSE TAG FOR VEHICLES.

Application filed April 13, 1922. Serial No. 552,249.

To all whom it may concern:

Be it known that I, WILMER A. REIN, a citizen of the United States, residing at town of Pleasant Springs, in the county of Dane 5 and State of Wisconsin, have invented a new and useful License Tag for Vehicles, of which the following is a specification.

This invention relates to license tags for vehicles and more particularly to those in 10 which a permanent number is used and having a year and state carrying element detachably connected therewith.

The object of the invention is to provide a license tag plate of this character the year 15 carrying element of which has means to prevent its being used except in connection with the license for which it was designed.

Another object is to provide a tag of this 20 character on which a permanent license number is stamped, the same registration number being used in connection with each vehicle during the entire life of the vehicle, and which carries a detachable plate bearing the year number, the letter of the State 25 in which the license is registered and the license number which corresponds with the permanent number on the tag plate proper.

Another object is to so construct a year 30 carrying plate that it will indicate at a glance whether or not the vehicle owner has renewed his license.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the 35 scope of what is claimed without departing from the spirit of the invention.

In the accompanying drawings:—

Figure 1 represents a front elevation of the tag constructed in accordance with this 45 invention.

Fig. 2 is a detail longitudinal section taken on the line 2—2 of Fig. 1, and

Fig. 3 is a transverse section taken on the line 3—3 of Fig. 1.

50 In the embodiment illustrated a license tag plate 1 is shown such as is ordinarily used for motor vehicles having pressed or stamped out thereon the license number shown at 2. The plate 1 carries at one end 55 thereof a detachable year plate 10 which is of a length preferably corresponding to the

width of plate 1 and which is designed to be slidably mounted in the seat formed on the end of plate 1 by flanges 3 and 4 bent inwardly at the end and one side edge respectively of said plate 1 and which cooperate with a tongue 5 struck out of plate 1 at a point spaced from the end flange 3 a distance corresponding to the width of plate 10 and which is bent to form a guide so that the 60 plate 10 may be slipped into the seat transversely of plate 1 and which when so inserted will be retained in position by binding engagement of the flanges and tongue and also by securing bolts which pass 65 through openings 11 and 12 in the corners of plate 10 and through registering openings such as those shown at 6 in plate 1.

The plate 10 is designed as a license renewal plate one of which is issued each year 70 and carries on its face the year number here shown at 13, and a letter 14 which indicates the State in which the license was granted. On this plate 10 between the letter 14 and the year number 13 is positioned the license 75 number 15 which corresponds with the number 2 used on the plate 1. By so forming this renewal plate, it will be rendered theft proof since it can be used legitimately only in connection with the plate 1 bearing the 80 license number corresponding with that on the plate 10.

In the use of this tag, plate 1 is issued when the vehicle is first registered and the 85 number 2 given thereon constitutes the license number which is used continuously throughout the life of the vehicle thus requiring one registration only of each vehicle. It is of course understood that the renewal tag or plate 10 is issued yearly and is colored 90 differently each year so as to indicate at a glance whether or not a vehicle owner has 95 renewed his license.

The use of the single license number on a vehicle during its entire life or during its 100 ownership by a certain party according to the laws of the State would permit such number being retained among the records of each city or town so that all cars in the immediate vicinity may be easily identified, 105 which is desirable in cases of arrest.

Further advantages incident to the issue of the small plate 10 yearly are that a small amount of material only is required for the manufacture of such plate, a saving in 110 freight or express in transporting the plates from the point of manufacture to the point

of distribution; and the convenience in changing one renewal plate for another.

I claim:—

A vehicle license tag comprising a plate 5 having a license number impressed thereon and provided with inturned flanges at one end and one side edge and with an out struck tongue opposed said end flange to form a seat thereon to receive and support a year 10 carrying plate, and a renewal or year carry-

ing plate of a size to slide between one of said flanges and said tongue and to rest on the other flange.

In testimony that I claim the foregoing as my own, I have hereto affixed my signature 15 in the presence of two witnesses.

WILMER A. REIN.
